UNITED STATES PATENT OFFICE.

JAMES W. CHILSON, OF DAYTON, IOWA.

PUMP PISTON.

Application filed July 6, 1920. Serial No. 394,313.

To all whom it may concern:

Be it known that I, JAMES W. CHILSON, a citizen of the United States, and a resident of Dayton, in the county of Webster and State of Iowa, have invented a certain new and useful Pump Piston, of which the following is a specification.

The object of my invention is to provide a piston for pumps or the like of simple, durable and inexpensive construction.

More particularly it is my object to provide a pair of washer members, having inclined coacting surfaces thereon and a pliable plate or strip of material placed therebetween and adapted to be moved to various positions, due to the upward and downward stroke of the piston.

Still a further object is to provide in such a device, a pliable strip of material held between a pair of coacting washer members or guides, the parts being so arranged that when the piston is moved downwardly, in order to cause air to be ejected from the pump or the like, the back pressure will cause the pliable strip of material to be forced outwardly at all points against the inner surfaces of the pump or cylinder.

With these and other objects in view, my invention consists in the construction, arrangement and combination of the various parts of the device, whereby the objects contemplated are attained as hereinafter more fully set forth pointed out in my claims and illustrated in the accompanying drawings, in which—

Figure 1 shows a vertical, central, sectional view taken through a portion of a pump or cylinder with my improved piston member shown in cross section; and

Figure 2 shows a horizontal, central, sectional view taken on line 2—2 of Figure 1.

In the accompanying drawings, I have used the reference numeral 10 to indicate an ordinary pump cylinder, which is provided with the piston rod 11, which is formed with a contracted portion 12 near its lower end.

The contracted portion 12 is provided with the screw-threaded end 13.

My improved piston comprises an upper washer member 14, which is provided with a central opening 15 of substantially the same diameter as the contracted portion 12 of the piston rod 11. The washer member 14 is provided with an upwardly and outwardly extending annular flange 16, which forms the inclined surface or edge 17.

A second or lower washer member 18, which is provided with a central opening 19, is received on the contracted portion 12 of the piston rod 11. The washer member 18 is provided with an annular flange 20, which is also provided with an inclined surface, which is substantially formed at the same angle of inclination as is the inclined portion 17 of the washer 14.

Received between the washers 14 and 18 is the strip or disc of pliable material 21, which may preferably be made of leather or of some other material, which is easily moved to various positions and capable of conforming to the contour of any surface which it may be placed adjacent to.

The pliable material 21 is provided with a downwardly extending flange portion 22 and the upwardly inclined extending portion 23. The portion 23 is received between the inclined surface 17 of the washer 14 and the coacting inclined portion 20 of the washer 18.

The overall diameter of the washer 14 is substantially greater than the diameter of the washer 18. The purpose of this is to provide an inclined surface on which the pliable material 21 may conform to, when there is a great amount of pressure applied to the under side of the piston.

In Figure 1 of the drawings, the dotted lines indicate the position of the pliable material 21 on the downward stroke of the piston or in the direction indicated by the arrow 25.

It will be understood that the air pressure on the downward stroke of the piston will cause the pliable material 21 at the flange 22 to be moved or forced outwardly at all points against the inner surface of the wall of the cylinder 10. The pressure will also cause the inclined portion 23 of the pliable material 21 to conform to the inclined surface 17 of the washer 14, thus tending to cause the flange 22 and the pliable material 21 to be moved outwardly as far as possible, thus forming an absolute air retaining compartment between the lower side of the cylinder 10 and the piston.

Received on the screw-threaded portion 13 of the piston rod is the nut 24, which holds the three parts which form the piston, namely, the washers 14 and 18 and the pliable material 21, against each other.

The contracted portion 12 of the piston rod 11 forms a shoulder against which the

upper surface of the washer 14 will rest, thus holding the piston substantially rigid onto the piston rod 11.

It will be understood that the important parts of my device are the coacting inclined surfaces and the pliable material, which is capable of easily conforming to the contour of inclined surfaces, in order to cause the pliable material to be forced outwardly at all points, due to the back pressure of the pump, thus forming a washer or piston capable of retaining air and preventing it from leaking.

As shown in Figure 1, the lower end of the cylinder is the end toward which the piston moves on its compression stroke. As illustrated in this figure, it will be noted that the washer 14 has its flange extending outwardly and upwardly, and it will be also noted that the disc of pliable material 21 has a portion spaced from its periphery that extends upwardly and outwardly, and then its peripheral portion extends straight downwardly approximately parallel with the sides of the cylinder. By this arrangement, when the piston is making its compression stroke the pressure of the air between the downwardly extending portion 22 and the periphery of the washer 14 will cause the upwardly and outwardly extending part 23 of the disc 20 of pliable material to wedge between the inclined flange 16 of the washer 14 and the adjacent portion of the cylinder, thus forcing the upper part of the flange 22 out against the cylinder by the combined action of the air pressure outwardly and the action of the air pressure forcing the adjacent portion of the pliable disc upon the inclined portion 16 of the washer 14. In other words, the lower part of the flange 22 is forced outwardly against the cylinder by the air pressure alone, and the upper part of the flange 22 is forced outwardly against the

cylinder by the air pressure upon the pliable disc forcing it against the inclined surface 16, which causes the upper portion of the said flange 22 to also move outwardly and upwardly until it is forced against the interior of the cylinder.

Some changes may be made in the construction and arrangement of my pump piston, without departing from the essential features and purposes of my invention, and it is my intention to cover by my claim any modified forms of structure or use of mechanical equivalents, which may be reasonably included within their scope.

I claim as my invention:

A device of the class described, comprising a piston rod, two washers and a pliable disc mounted upon the said piston rod with the pliable disc between them, the lower washer being provided at its periphery with a flange, the outer portion of the upper surface thereof being extended upwardly and outwardly, the periphery of the washer being substantially parallel with the piston rod, the upper washer having its periphery extended upwardly and outwardly and the pliable disc having a portion near its periphery extended upwardly and outwardly, and its peripheral portion extended downwardly overlapping the periphery of the lower disc, and terminating near the lower edge of the lower disc and being free to move inwardly and outwardly toward and from the periphery of the lower disc, and whereby when the piston is moved downwardly the peripheral portion of the pliable disc will be moved outwardly by the combined action of the resistance that is being applied to the piston and its engagement with the inclined periphery of the upper washer.

Des Moines, Iowa, June 16, 1920.

JAMES W. CHILSON.
